AIR CONDITIONING SYSTEM

Nelson T. Branche, Toledo, and Francis R. Bichowsky, Ottawa Hills, Ohio, assignors to Surface Combustion Corporation, Toledo, Ohio, a corporation of New York

Application November 21, 1935, Serial No. 50,827

3 Claims. (Cl. 183—15)

This invention relates to fluid conditioning processes and apparatus and more particularly to the application of such processes and apparatus to houses or enclosures containing an existing warm air system.

Among the objects of this invention is to provide an improved apparatus for conditioning fluids adaptable for interconnection with an existing warm air system; improved processes of conditioning air in an existing warm air system; improvement in apparatus for conditioning air in an existing warm air system for both winter and summer applications.

This invention will be better understood and further advantages and objects will be pointed out in the following specification taken in connection with the accompanying drawing.

In the single figure of the drawing features of this invention are shown as applied to an existing warm air system only shown in part.

Considering the drawing in greater detail, a system is shown as assembled below an enclosure 10 in which the air is to be conditioned. The enclosure 10 is normally connected to a warm air system comprising a warm air furnace 12 having a suitable heating means 14 and a duct system interconnecting the warm air furnace with the enclosure. This duct system is shown as comprising a duct 16 opening through a side wall 18 of the enclosure being controllable by damper means 20 and a duct 22 going from the furnace to the enclosure by way of a floor 24 of the enclosure, likewise having controlling means 26. Other ducts 28 and 30 connect the system to other portions of the enclosure which may be a single room or a plurality of rooms. The air from the enclosure is normally returned to the warm air furnace by way of a duct system a portion of which would connect the floor opening 32 to the return air inlet 34 of the warm air furnace. This portion of the duct system is not shown because of the connecting of the conditioning apparatus and warm air system together.

The conditioning means is illustrated as being enclosed in a housing 36. This housing 36 is connected to the return air opening 32 by way of the duct 38 which is connected to an opening 40 at the top of the housing and a further opening 42 is provided in a portion of the housing allowing for a different manner of introducing the air to be conditioned. The conditioning apparatus housing is also connected to the warm air system by a duct 44 connecting the lower part of the conditioning housing with the return air inlet 34 of the warm air furnace.

The air conditioning apparatus includes upper and lower chambers 46 and 48 which are connected together by means of openings 50 and 52 which latter openings are controlled by hand operated dampers 54 and 56. The chambers 5 are so arranged that when the damper 54 is closed and the damper 56 is open, a substantially U-shaped chamber is provided, the upper portion of the U being in communication with the duct 38 by way of the opening 40 and the filter 58, the lower portion of the U being in communication with the warm air furnace by way of the duct 44 and a fan 60. This construction allows the apparatus to be constructed as a unit, requiring only half the floor space normally needed, a single piece of equipment for shipment, and a more readily assembled piece of apparatus from the production standpoint. The system is flexible from the standpoint that the damper 54 may be entirely open or entirely closed or partly open with the damper 56 remaining open. Under such circumstances, the air being conditioned may partly by-pass the chambers 46 and 48 by passing directly through the opening 50 to the fan 60. In summer use the damper 54 will be normally closed and the damper 56 normally open so that all the air will be treated in the housing 36. This construction is normally arranged so that all of the air entering the housing will pass through the filter 58. In winter operation the damper 56 may be closed and the damper 54 open so that the air will pass into the upper chamber through the filter and to the lower chamber by way of the opening 50 and thence into the fan 60 for passage to the warm air system. It will readily be appreciated that by the arrangement described a bypass system is provided giving complete control within a unit housing thereby avoiding complicated and unsightly duct systems to provide the same flexibility.

The upper chamber 46 is shown as being provided with a plurality of contacting devices which may partake of any form; however, for the purpose of simplicity being shown as a group of spray contactors 64, 66, and 68. These spray devices are connected by a pipe system 70 to a suitable source of conditioning medium which may be hygroscopic liquid. The fluid 72 from the sprays after contacting the air which is passed through the chamber 46 will be collected by the sump 74 and returned by way of the pipe 76 to a lower sump 78. This connection 76 may also be by way of a direct connection to the pipe 80 which returns the fluid to the source of supply or regeneration. In the lower chamber 48 is

positioned a second spray tower comprising a plurality of spray devices 82 connecting to the supply pipe 84 which latter pipe is connected by way of the pipe 86 to a pump 88. This pump is connected by way of the pipe 90 to a sump 92 which collects the excess fluid from the sprays 82. This latter spray in the lower chamber is preferably of water to humidify the air whereas the upper spray preferably uses a hygroscopic liquid for the purpose of drying the air. The contactors in the upper chamber may use water and those in the lower chamber may use a hygroscopic liquid or both sets may use a hygroscopic liquid. In these latter connections, however, the 15 eliminator 94 will be positioned between the contactor 82 and the fan 60 to keep the air stream free of drying agent. Interposed between the two spray chambers is an eliminator 94 of any appropriate type which may collect any droplets 20 of conditioning fluid which have been entrained in the air stream and will return the same to the dehumidifying system by way of the sump 78. Appropriate baffles 96 and 98 may be incorporated 25 for the purpose of directing the air stream with reduced turbulence.

Although a preferred embodiment of this invention is shown and described, variations within the true spirit and scope of the appended claims are to be included.

30 What we claim is:

1. An air conditioning system for conditioning spaces of occupancy adapted to be heated by a pre-existing warm air furnace system comprising 35 in combination therewith, a housing having inlet and outlet openings, upper and lower chambers in said housing in communication with said openings, a filter in the upper chamber arranged to

filter all the air passing through the system, means in said upper chamber for contacting air with a hygroscopic liquid spray, a fan in said lower chamber arranged to effect the movement of air through said system, means for humidifying the 5 air in said lower chamber, and means controllably interconnecting said chambers whereby air drawn through the filter by said fan may pass either directly into the warm air furnace system or may first pass through said drying and humidifying 10 means and then into said furnace system.

2. Air conditioning apparatus comprising a housing having inlet and outlet openings; upper and lower chambers in said housing; liquid contact devices in said chambers; means for effecting the contact of the air to be conditioned with a liquid spray in the lower chamber, a filter in said upper chamber, and means controllably interconnecting said chambers whereby to form a substantially U shaped air tunnel for contacting 20 the filtered air or for bypassing the filtered air back to an enclosure.

3. Air conditioning apparatus comprising a housing having inlet and outlet openings, upper and lower chambers in said housing in communication with said openings, means adjacent the inlet opening arranged to filter all the air passing through the housing, means in said chamber for contacting air with a liquid, means interiorly of said housing for effecting the movement of air through said housing, and means controllably interconnecting said chambers whereby air drawn through said first named means may pass through said air and liquid contact and then out of said housing or may pass directly out of the housing. 30
